TREATMENT OF HYDROCARBONS

Gerald L. Eaton, Philadelphia, Pa., assignor, by
mesne assignments, to The Polymerization
Process Corporation, Jersey City, N. J., a cor-
poration of Delaware

Application March 27, 1934, Serial No. 717,611

11 Claims. (Cl. 196—10)

This invention relates to the thermal conversion of hydrocarbons, and more particularly to the production from low-boiling hydrocarbons of relatively higher boiling point hydrocarbons including hydrocarbons boiling within the boiling range of commercial motor fuels and having valuable anti-detonation characteristics and being otherwise suitable as motor fuel.

An object of this invention is to provide a process whereby low-boiling hydrocarbons, including especially hydrocarbons which are normally gaseous, such as occur in natural gas or in petroleum refinery gas, and particularly in gases from cracking still operations, may be converted into relatively higher boiling and preferably liquid, or liquefiable, hydrocarbons under conditions which minimize the formation of undesirable products, such as tar and fixed gases including hydrogen and methane.

20. In the practice of this invention, lower boiling hydrocarbons which are preferably wholly or in major proportion normally gaseous are subjected to conditions which effect cracking and production of unsaturated hydrocarbons, and the products of the cracking treatment are subjected to conditions which involve a lower temperature than that employed in the cracking treatment and promote polymerization of the cracked hydrocarbons into relatively higher boiling hydrocarbons and preferably into hydrocarbons suitable as constituents of motor fuel. In accordance with this invention, the conditions created and maintained in the several steps are so adjusted and related as to effect a maximum conversion of 35 the hydrocarbons treated into desirable products and a minimum conversion thereof into undesirable products.

In the practice of this invention, the hydrocarbons to be treated are compressed prior to being subjected to heat and are maintained under pressure during the cracking operation and the polymerizing operation. The pressure maintained in the polymerizing step is essential to the polymerization desired; and compression before cracking avoids the necessity for compressing hot gases between the cracking and polymerizing steps, or, in the alternative, the necessity for cooling, compressing, and reheating of the cracked gases at that point in the operation. Also, I have found that in procedure in accordance with this invention, the pressures selected for promotion of polymerization are not such as will deleteriously affect the progress and results of the cracking operation; and the employment of such pressures in the cracking operation appears to minimize

the formation of hydrogen to such extent as to render unnecessary the removal thereof from products passing from the cracking operation to the polymerizing operation. Moreover, the employment of pressure minimizes the size of equipment necessary in apparatus employed in the practice of my process. The pressure employed depends upon and must bear a more or less definite relation to other conditions adjusted in accordance with the principles of this invention, 10 the requirements of the polymerizing step in this regard being of great importance. To this end, pressures of the order of from 200 to 3000 lbs. per sq. in., and more preferably pressures of the order of from 500 to 1500 lbs. per sq. inch, 15 are employed in the practice of this invention.

In the practice of this invention, the conditions of temperature, pressure, and time employed in the cracking operation are so co-ordinated as to give definite results of a particular nature, and 20 are so co-ordinated with the conditions preserved and results effected in the polymerizing step that maximum production of desirable products with minimum production of waste is achieved. Thus, the temperature and time of the cracking operation are so chosen that, under the existing pressure conditions, the content of unsaturates and polymers in the products leaving the cracking operation will yield a maximum of desired polymers as a result of the polymerizing step, with 30 minimum production of waste products. The higher the temperature employed in the cracking operation, the more rapid is the production of fixed and inert gases and tar. The higher the temperature employed, the greater is the concentration attainable of unsaturates plus polymers provided the duration of the high temperature is correctly adjusted. Thus, for example, with a cracking temperature of 1100° F., employed in connection with a charge gas consisting 40 principally of C₃ and C₄ hydrocarbons, as high a content (percentage by weight) of unsaturates plus polymers cannot be achieved as can be achieved by employment of higher temperatures; at the lower temperature it is not necessary to 45 adjust the time with great care in order to obtain the maximum concentration of unsaturates plus polymers, any period of time within a relatively wide range giving such maximum concentration. On the other hand, when a temperature of 1300° F. is employed with such charge gas, 50 the content of unsaturates plus polymers rises to a higher maximum, but the time must be adjusted with care, because excessive time leads to rapid reduction of such content; and such ex-

55

cessive maintenance of high temperatures also extends the production of waste products, such as inert gases and tar.

Accordingly, in the practice of this invention the relation of time and temperature in the cracking operation is preferably so adjusted as to cause that operation to produce a maximum content of unsaturates plus polymers, and such an adjustment leads to the achievement of the desirable 10 conditions and results above set out, including the maintenance of such correlation of cracking and polymerizing conditions as will give large production of desirable products. Again, it is to be noted that high temperatures and wasteful extension of 15 cracking operation are conducive to the production of benzol, whereas the preferable conditions in the practice of this invention are conducive to the production of hydro-aromatic and cyclic hydrocarbons; and such hydro-aromatic and cyclic 20 hydrocarbons have anti-detonation qualities, when actually blended with motor fuel, which are in some respects equal to if not greater than those qualities of benzol.

In the practice of this invention the temperatures 25 attained in the cracking zone are within the range of from approximately 1000° F. to 1500° F., and more preferably from about 1200° F. to 1400° F., when the pressure maintained is of the order of from 200 to 3000 pounds per sq. inch, and the 30 duration of the elevated temperature is adjusted as above pointed out and hereinafter more specifically exemplified, suitable cracking periods being of the order of, for example, from 0.2 to 0.5 second at 1350° F., or from 10 to 30 seconds while 35 the temperature of the hydrocarbons is being raised from 1050° F. to 1200° F., when, for instance, a charge gas consisting principally of C₃ and C₄ hydrocarbons is being converted. Inasmuch as the employment of temperatures above 40 the minimum at which cracking begins, results in the occurrence of cracking while the temperature of the hydrocarbons is being raised from such minimum to the maximum temperature employed, account must be taken of the time required for 45 that rise in temperature as well as of the time during which the hydrocarbons are at the maximum temperature. In practice it is frequently advantageous to raise the temperature to a predetermined value and thereupon effect the cooling 50 between the cracking and polymerizing operations, thus making it necessary to take into account only the time during which the temperature is rising from a temperature at which substantial cracking occurs, e. g. rising from 1050° F., up to 55 the predetermined maximum temperature. I have found that the yield of unsaturates and the yield of unsaturates plus polymers decreases when, for a given cracking temperature, the cracking time is extended for too long a period, 60 or when, for a predetermined heating period, the temperature is increased beyond the optimum for that period. I have found that adjustment of the time and temperature, at the pressure employed, in such relation as to produce a maximum 65 concentration of unsaturates in the hydrocarbons leaving the cracking operation, facilitates a maximum yield of desired polymers and a minimum yield of waste products, such as inert or fixed gases and tar, and results in such low content of 70 hydrogen as to render unnecessary the removal thereof from the system prior to the polymerizing operation.

Having completed the cracking operation, which involves an endothermic reaction and requires addition of heat, the polymerizing opera-

tion, which is exothermic, is carried out; but I reduce the temperature of the gases passing from the cracking operation to the polymerizing operation. This reduction of temperature slows down or annuls further cracking of the hydrocarbons treated and tends to minimize or prevent further degradation of valuable hydrocarbons into fixed or inert gases and tar or other waste products. Preferably, the cooling is effected in such manner as to preserve such pressure as is desired in the 10 subsequent polymerizing operation; and the cooling may be effected by addition to the products passing from the cracking operation of a cooling medium, such as naphtha, heavy oil, water, or inert or hydrocarbon gas, or it may be effected by 15 conventional heat exchange. The cooling will effect a reduction of temperature sometimes amounting to several hundred degrees, thus bringing the temperature of the products passing from the cracking zone at a temperature approximately 20 within the range of from 1000° F. to 1500° F., down to a temperature approximately within the range of from 700° F. to 1200° F., and preferably 25 within a range of from 800° F. to 1050° F., the pressure being maintained within the range of from approximately 200 to 3000 lbs. per sq. in.

The desired polymerization may be effected with or without the aid of a catalyst, and the carrying out of this operation in a separate zone facilitates the adjustment of temperature, time, and pressure conditions. The pressure being of the order of from 200 to 3000 lbs. per sq. in., the time and temperature are adjusted somewhat as a compromise between theoretical and practical considerations. A long period of time at a relatively low temperature minimizes degradation and promotes yield but requires apparatus of large capacity. At higher temperatures, polymerization can be effected more rapidly, but simultaneous degradation is promoted. In any event, the 40 polymerization tends to increase the content of polymers and decrease the content of unsaturates.

For example, when reaction-accelerating catalysts are not employed, if the charge gas consists principally of C₃ and C₄ hydrocarbons, and such gas, under a pressure of substantially 1000 lbs. per sq. in., leaves the cracking zone with a 40% content by weight of unsaturates and the temperature of the polymerizing zone is held at 1000° F., for a period of from 4 to 8 minutes, a 50 yield of 15% to 17% by weight of motor fuel hydrocarbons results, whereas if that temperature is held at 950° F. for a period of 8 to 15 minutes a yield of 17% to 20% by weight of motor fuel hydrocarbons results; if that temperature is held at 900° F., for a period of from 20 to 40 minutes, a yield of 21% to 23% by weight of motor fuel hydrocarbons results; and if that temperature is held at 800° F. for a still longer period a still higher yield of such hydrocarbons results. The 60 use of lower temperatures and longer times gives less production of hydrogen, methane, ethane, and tar. This example serves to indicate the conditions affecting the choice of temperatures and pressures in the polymerizing operation, but in any event the polymerizing operation usually requires periods of time measured in minutes as contrasted with periods of time measured in seconds or fractions of a second in the cracking operation. As a further example, when catalysts 70 are not employed, the polymerizing time may be of the order of from about 10 to about 40 minutes at temperatures of the order of 900° F., and pressures of the order of 1000 lbs. per sq. in., whereas such time may be of the order of from 75

about 2 to about 15 minutes for temperatures of about 1000° F., the pressure being the same.

In adjusting the temperature and time conditions for the pressure employed, both in the cracking operation and the polymerizing operation, it is to be recognized that conditions employed in connection with hydrocarbon gas of one composition must be adjusted to effect comparable results in connection with hydrocarbon gas of a different composition, higher content of hydrocarbons having a higher number of carbon atoms usually requiring lower temperatures and shorter effective periods of time.

In the practice of this invention, the products passing from the polymerizing operation are subjected to cooling which condenses certain constituents thereof, and the products may be separated into various fractions, for example, fixed gases such as hydrogen and methane (and preferably ethane), tar, desired polymers, and gases suitable for recycling through the system.

At this point it will appear that practice in accordance with this invention provides for the production of desirable liquid or liquefiable polymers from hydrocarbon mixtures which are wholly or in major proportion normally gaseous; that the yield of desired products is high and the degradation of hydrocarbons is minimized; that the advantages may flow from limitation of the conversion in the cracking operation while extending the conversion in the polymerizing operation; and that the co-ordination of the conditions in the cracking operation with those existing in the polymerizing operation leads to an avoidance of extensive production of hydrogen and inert gases and avoidance of resulting waste, and interference with proper procedure toward the desired products.

To assist further in an understanding of this invention, there is described herein a specific example of the application thereof, with the understanding that this invention is not limited thereto nor to the particular apparatus shown in connection with the description thereof.

Hydrocarbon gas, for example, such as that taken from an oil cracking unit, is passed from a source (not shown) through valve-controlled pipe 1 to compressor 2 wherein it is compressed to a pressure of the order of from 200 to 3000 lbs./sq. in., and delivered through valve-controlled pipe 3 to the cracking tubes 4 of the furnace 5. Herein, the compressed gases are heated to a temperature of from about 1000° F. to about 1500° F., for a period of time sufficient to effect a substantial conversion of the stable constituents of the gas to polymerizable unsaturates. The heated products from the cracking tubes 4, at a temperature of from substantially 1000° F. to 1500° F., and under a pressure of the order of from 200 to 3000 lbs./sq. in., are passed to transfer line 6, and thence into reaction chamber 7. However, either during their passage through the transfer line or at their point of introduction into the reaction chamber, the heated products are cooled from a temperature of the order of from 1000° F. to 1500° F., to a temperature of from substantially 700° F. to 1200° F., whereby further cracking is substantially prevented. The step of cooling may be accomplished in various ways. For example, a portion of the compressed hydrocarbons from pipe 3 may be passed through pipe 8, cooler 9, valve-controlled pipe 10 and pipe 11 into transfer line 6, valves 12' and 13' being closed, or compressed recycle hydrocarbons may be introduced into line 6 from valve-controlled

pipe 13, or a cooling medium such as, for example, inert gas, hydrocarbon gas, naphtha, heavy oil, water or steam may be passed, under pressure, from a supply not shown, through valve-controlled pipe 12 and pipe 11 into transfer line 6. Cooling of the heated products from the cracking tubes 4 may be effected, if desired, by the installation of conventional heat exchange apparatus in the transfer line 6. Regardless of the cooling means used, the temperature of the heated products is reduced to the order of from about 700° F. to about 1200° F., at which temperature further cracking is substantially prevented and at which polymerization is effected.

The thus cooled products in the reaction chamber 7 are maintained at a temperature of from about 700° F. to about 1200° F., and under a pressure of from substantially 200 to 3000 lbs./sq. in., for a period of time sufficient to effect the most economical degree of conversion of the unsaturates into desirable polymers. The products from the reaction chamber 7 are passed, by means of valve-controlled pipe 14 and pipe 15 into separator 16.

In certain instances, it may be desirable to effect a partial cooling of the products which pass from the reaction chamber 7 to the separator 16 by injecting a cooling medium, such as water or hydrocarbon oil, into the vapor stream from said chamber. The coolant may be introduced under pressure, from a source not shown, into pipe 16 by means of valve-controlled pipe 17. Partial separation of tar is effected in vessel 16, the tar being withdrawn from the bottom thereof through valve 18, pipe 19, pipe 20 and valve 21, and passed to storage or otherwise disposed of. The hydrocarbon vapors, and water vapor if present, are passed from the top of the separator 16, at a temperature preferably below 800° F., through valve 22, cooler 23 and pipe 24 into water separator 25. Pressure may be reduced by means of valve 22, for example, from about 200 to about 3000 lbs./sq. in., to about 200 to 1000 lbs./sq. in., and the temperature of the vapors passing through cooler 23 may be reduced from about 800° F. or less, to about from 35° F. to 250° F., thereby permitting the bulk of the water, when present, to separate from the hydrocarbons, said water being withdrawn from the separator 25 through valve-controlled pipe 26.

The hydrocarbon mixture comprising polymers, unconverted hydrocarbons, fixed gases and a small quantity of tar is passed from the water separator 25 through pipe 27 into reflux column 28 provided adjacent its top with a refrigerating coil 29. In the column 28 the hydrocarbon liquids are freed of the fixed gases, i. e., hydrogen and methane (and preferably also ethane), which are removed from the top of the column by means of pipe 30 and vented through valve 31, the coil 29 providing reflux which aids in the removal of higher boiling hydrocarbons from the gases. The hydrocarbon liquid withdrawn from the bottom of column 28 is forced, under a pressure of the order of from about 200 to 1000 lbs./sq. in. through heat exchanger 32, wherein the temperature is raised to about from 100° F. to 500° F. The heated hydrocarbon mixture is passed from the exchanger 32 through valve-controlled pipe 33 into fractionating column 34, provided with a heating coil 35. The pressure on the hydrocarbons introduced into column 34 is preferably reduced from about 200 to 1000 lbs./sq. in., to about 50 to 400 lbs./sq. in., by means of valve 33', the temperature of the material introduced into the

column being within the range, for example, of from about 100° F. to about 500° F. In column 34 the normally gaseous hydrocarbons are fractionated from the polymers and tar, the former being removed from the top of the column through pipe 36 and passed into partial condenser 37, from which any liquid condensed is withdrawn and returned to column 34 by means of valve-controlled pipe 38, pump 38a and valve-controlled pipe 38b, to serve therein as reflux.

The uncondensed gaseous hydrocarbons are removed from the top of partial condenser 37 and are passed through valve-controlled pipe 39 to compressor 40. The uncondensed gases are compressed therein to a pressure of the order of from about 200 to about 3000 lbs./sq. in., and may be recycled by means of pipe 41 and valve 42 to the cracking tube 4 for further heat treatment, or they may be passed, under the aforesaid pressure, through pipe 43, cooler 44 and valve-controlled pipe 45 into transfer line 6 to function as a coolant for the heated products from the cracking coil 4. In the event that the recycling of the unconverted hydrocarbon gases is not desired, said gases may be vented by means of valve-controlled pipe 39a.

The polymers and tar from the bottom of column 34 are passed under pressure, through pipe 45, valve 46, heat exchanger 47 and pipe 48 into fractionating column 49, provided with heating coil 50. This column is operated preferably at a temperature of from 200° F. to 500° F., and under a pressure of from atmospheric to 200 lbs./sq. in. Herein the polymers and tar are separated by fractionation. The polymers are removed as vapors from the top of the column through pipe 51 and passed to condenser 52 wherein condensation is effected, a portion of the liquid polymers then being returned as reflux to column 49 by means of valve-controlled pipe 53, and the remainder of the polymers being withdrawn to storage through valve-controlled pipe 54. Tar is drawn from the bottom of column 49 by means of valve-controlled pipe 55, and is removed from the system through pipe 20 and valve 21.

While in the above illustration I have shown a reflux tower (28) as a means of separating the fixed gases from the valuable hydrocarbons, I may substitute therefor, a flash drum wherein the uncondensed gases, in equilibrium with the liquid hydrocarbons, may be separated therefrom, under the proper conditions of temperature and pressure. Likewise, various modifications in the fractionating column 34 may be employed, or a different type of fractionating equipment, such as for example, an absorption system, may be utilized in place of columns 28 and 34. In general, the separation of the products of reaction may be accomplished by various means familiar to those skilled in the art, without departing from the spirit and scope of my invention. Furthermore, while I have shown the introduction of the cooling medium into the heated products from the cracking tube at a point intermediate between the cracking furnace and the reaction chamber, I may introduce said cooling medium into the reaction chamber itself, preferably in the proximity of the chamber inlet.

The following examples are given as illustrative of the results which may be obtained when operating in accordance with my process. In these examples, "naphtha", i. e., desirable polymers, is defined as that material boiling between 60° F. and 400° F. "Tar" is designated as material boiling above 400° F.

In Example I the charge was of natural gas source, and contained no unsaturates. The object of the thermal treatment in the cracking zone was to produce the maximum percentage of olefins plus naphtha, with the minimum production of hydrogen, methane, and ethane. The contact time given is approximately the optimum for the temperature employed. In this case the gas was heated continuously to a furnace outlet temperature of 1200° F., and the contact time tabulated is the time in which the gas was heating from 1050° F. to 1200° F.

Had the contact time at this temperature been either substantially less or substantially greater than that given, the conversion would not have been as satisfactory, since the amount of olefins plus naphtha would have been less than that tabulated. Also, if the time had been longer, the

amount of hydrogen, methane, and ethane would have been greater. By cooling immediately to the polymerizing temperature, after the proper cracking time, the production of naphtha in the process as a whole is markedly increased.

In Example II the charge was of refinery gas source and, since there were olefins already present in it, the reaction time for the optimum production of naphtha plus olefins was somewhat less at a given reaction temperature than with a charge from natural gas source.

In the examples given, it should be noted that there is a considerable content of unconverted hydrocarbons in the products leaving the polymerizing zone, and if recycling of these unconverted compounds is carried out quantitatively, in Example I the ultimate yield of naphtha would be of the order of 35% by weight as against a once thru yield of 17.1% by weight; whereas in Example II, the ultimate yield of naphtha would be of the order of 47% by weight, as against a once thru yield of 28% by weight.

One of the major advantages of my process consists in the fact that the entire stock is treated under the optimum conditions, so that by controlling the time of reaction the greatest ratio of valuable products to waste products is obtained. Under these conditions there remain considerable unconverted compounds which may again be passed through the apparatus to obtain the same high ratio of valuable to waste products.

Had the conversion been carried on for appreciably longer cracking times than the optimums disclosed herein, the once through yield of naphtha would have been slightly greater, but the ultimate yield would have been very markedly reduced.

With regard to the function of pressure in the two stages of my process, I find, in the cracking zone, that pressure has relatively little effect on the reaction other than its effect on contact time. In the polymerizing zone, however, the polymerization of unsaturates to naphtha is very greatly affected by pressure, particularly in the range below 200 lbs./sq. in., and unless the pressure is above this figure only slight conversion is obtained, in the absence of catalysts.

For brevity, herein and in the appended claims, the term "cooling medium" is to be understood to comprehend such agents as hydrocarbon oil, compressed hydrocarbon gases, water and steam. Also, when in the appended claims the term "a high superatmospheric pressure" is employed, it is to be understood to mean pressures of the order of 200 lbs./sq. in. or greater.

What I claim is:

1. The process of converting predominantly paraffinic normally gaseous hydrocarbons into polymers, which comprises heating said hydrocarbons under a high superatmospheric pressure to a temperature at which at least a portion of said hydrocarbons will decompose to form substantial quantities of unsaturates, cooling the heated products to a temperature to prevent further substantial decomposition and at which polymerization thereof takes place, introducing said cooled products without separation and while maintaining substantially the same pressure into a reaction zone wherein polymerization is effected during the passage of substantially all of the cooled products therethrough, and removing the products of reaction from the zone last mentioned.

2. The process of converting predominantly paraffinic normally gaseous hydrocarbons into

polymers, which comprises heating said hydrocarbons under a high superatmospheric pressure to a temperature at which at least a portion of said hydrocarbons will decompose to form substantial quantities of unsaturates, cooling the heated products to a temperature to prevent further substantial decomposition and at which polymerization thereof takes place, introducing said cooled products without separation and while maintaining substantially the same pressure into a reaction zone wherein polymerization is effected during the passage of substantially all of the cooled products therethrough, removing the products of reaction from the zone last mentioned, fractionally separating the products of reaction, and recycling unconverted hydrocarbons for further heat treatment.

3. The process of converting normally gaseous hydrocarbons into polymers, which comprises heating said hydrocarbons under a high superatmospheric pressure to a temperature of the order of from 1000° F. to 1500° F., whereby at least a portion of said hydrocarbons will decompose to form substantial quantities of unsaturates, cooling the heated products to a temperature of the order of from 700° F. to 1200° F., to prevent further substantial decomposition and at which polymerization thereof takes place, introducing the cooled products without separation and while maintaining substantially the same pressure into a reaction zone wherein polymerization is effected during the passage of substantially all of the cooled products therethrough, and removing the products of reaction from the zone last mentioned.

4. The process of converting predominantly paraffinic normally gaseous hydrocarbons into polymers, which comprises heating said hydrocarbons under a high superatmospheric pressure to a temperature at which at least a portion of said hydrocarbons will decompose to form substantial quantities of unsaturates, cooling the heated products to a temperature to prevent further substantial decomposition and at which polymerization takes place by introducing thereto into a cooling medium, passing said cooled products without separation and while maintaining substantially the same pressure into a reaction zone wherein polymerization is effected during the passage of substantially all of the cooled products therethrough, and removing the products of reaction from the zone last mentioned.

5. The process of converting predominantly paraffinic normally gaseous hydrocarbons into polymers, which comprises heating said hydrocarbons under a high superatmospheric pressure to a temperature of the order of from 1000° F. to 1500° F., whereby at least a portion of said hydrocarbons will decompose to form substantial quantities of unsaturates, cooling the heated products to a temperature of the order of from 700° F. to 1200° F., to prevent further substantial decomposition and at which polymerization takes place by introducing thereto into a cooling medium, passing the cooled products without separation and while maintaining substantially the same pressure into a reaction zone wherein polymerization is effected during the passage of substantially all of the cooled products therethrough, and removing the products of reaction from the zone last mentioned.

6. The process of converting predominantly paraffinic normally gaseous hydrocarbons into polymers, which comprises heating said hydrocarbons under a high superatmospheric pressure

to a temperature at which at least a portion of said hydrocarbons will decompose to form substantial quantities of unsaturates, maintaining such temperature and pressure conditions for such time as will give in the products leaving the cracking operation substantially the maximum content of polymers plus unsaturates attainable at such temperature, cooling the heated products to a temperature to prevent further substantial decomposition and at which polymerization thereof takes place, introducing said cooled products without separation and while maintaining substantially the same pressure into a reaction zone wherein polymerization is effected during the passage of substantially all of the cooled products therethrough, and removing the products of reaction from the zone last mentioned.

7. The process of converting predominantly paraffinic normally gaseous hydrocarbons into polymers, which comprises heating said hydrocarbons under a high superatmospheric pressure to a temperature at which at least a portion of said hydrocarbons will decompose to form substantial quantities of unsaturates, introducing a part of the hydrocarbons from the same source as those being heated into contact with heated products to cool them to a temperature to prevent further substantial decomposition and at which polymerization thereof takes place, introducing said cooled products without separation and while maintaining substantially the same pressure into a reaction zone wherein polymerization is effected during the passage of substantially all of the cooled products therethrough, and removing the products of reaction from the zone last mentioned.

8. The process of converting predominantly paraffinic normally gaseous hydrocarbons into polymers comprising motor fuel, which comprises heating said hydrocarbons under a high superatmospheric pressure at least as great as that obtaining in the later mentioned reaction zone to a temperature at which at least a portion of said hydrocarbons will decompose to form substantial quantities of unsaturates, cooling the heated products to a temperature to prevent further substantial decomposition and at which polymerization thereof takes place, introducing substantially all of said cooled products without separation thereof into a reaction zone main-

tained at a high superatmospheric pressure wherein polymerization is effected during the passage of substantially all of the thus cooled products therethrough, and removing the products of reaction from the reaction zone to recover polymers therefrom.

9. The process of converting predominantly paraffinic normally gaseous hydrocarbons into polymers, which comprises heating said hydrocarbons under a pressure in excess of about 500 pounds per square inch to a temperature at which at least a part of said hydrocarbons will decompose to form substantial quantities of unsaturates, cooling the heated products to a temperature to prevent further substantial decomposition and at which polymerization thereof takes place, introducing said cooled products without separation and while maintaining substantially the same pressure into a reaction zone wherein polymerization is effected during the passage of substantially all of the cooled products therethrough, and removing the products of reaction from the zone last mentioned.

10. The process of converting predominantly paraffinic normally gaseous hydrocarbons into polymers comprising motor fuel, which comprises heating said hydrocarbons under a high superatmospheric pressure at least as great as that later mentioned for the reaction zone to a temperature at which at least a portion of said hydrocarbons will decompose to form substantial quantities of unsaturates, cooling the heated products to a temperature to prevent further substantial decomposition and at which polymerization thereof takes place, introducing substantially all of said cooled products without separation thereof into a reaction zone maintained at a pressure in excess of about 500 pounds per square inch wherein polymerization thereof is effected during the passage of substantially all of the thus cooled products therethrough, and removing the products of reaction from the reaction zone to recover polymers therefrom.

11. A process in accordance with claim 10 wherein a pressure in excess of about 500 pounds per square inch is maintained on said hydrocarbons during decomposition thereof to unsaturates.
